DESIGN FOR A TRAVELING BAG

Martin L. Lee, Brooklyn, N. Y.

Application February 2, 1935, Serial No. 55,209

Term of patent 3½ years

To all whom it may concern:

Be it known that I, Martin L. Lee, a citizen of the United States, and resident of New York city, Borough of Brooklyn, in the county of Kings and State of New York, have invented a certain new, original, and ornamental Design for Traveling Bags, of which the following is a specification, reference being had to the accompanying drawing, forming a part thereof, and of which Figure 1 is an isometric perspective view, and Fig. 2 is a top plan view of a traveling bag showing my new design.

I claim:

The ornamental design for a traveling bag substantially as shown.

MARTIN L. LEE.
